UNITED STATES PATENT OFFICE.

CHARLES EDWARD HAVILAND, OF LIMOGES, FRANCE.

DESIGN FOR A COVER-DISH.

SPECIFICATION forming part of Design No. 22,620, dated July 18, 1893.

Application filed June 22, 1893. Serial No. 478,513. Term of patent 14 years.

To all whom it may concern:

Be it known that I, CHARLES EDWARD HAVILAND, a citizen of the United States, residing at the city of Limoges, in the Republic 5 of France, have invented and produced a new and original Design for a Cover-Dish and other Articles, of which the following is a specification, reference being had to the accompanying drawings, forming part thereof, and in 10 which—

Figure 1 is a side elevation of a cover-dish bearing and incorporating my design. Fig. 2 is a top view of same; and Fig. 3 is a vertical section of a portion of same on the dotted 15 line 3—3 of Fig. 2.

The leading feature of my design consist of the ornamental form and configuration of the dish, substantially as illustrated in the accompanying drawings.

20 The sides of the dish are composed of the scalloped sections A, and are slightly concave along their upper portions and thence extend downward and outward to a point or line at which they abruptly turn inward and down-

ward to the base B, whose edge bears the line 25 of ornate scalloped beading C and, at intervals, the ornamented surfaces D inclosed at opposite sides by said beading. At opposite sides of the body of the dish are the handles E representing conventionalized foliate ornamentation. The cover F has along its scalloped edges the ornamentation consisting of the line of scalloped beading G and, at intervals, the ornate surfaces H inclosed at opposite sides by 30 said beading. At the center of the cover F is 35 the scalloped raised portion I bordered along its edges by the ornamental beading J and bearing at its center the ornamental handle K.

What I claim is—

The design for a cover-dish and other articles, substantially as shown and described. 40

Signed at the city of New York, in the county and State of New York, this 20th day of June, A. D. 1893.

CHARLES EDWARD HAVILAND.
